LOBING SWITCH

Carl F. Schunemann, Euclid, Ohio, assignor to Thompson Ramo Wooldridge, Inc., a corporation of Ohio

Application January 31, 1956, Serial No. 562,391

1 Claim. (Cl. 343—876)

This invention relates to a lobing switch and more particularly to a switch for an antenna lobing system or the like in which a movable contact is sequentially connected to a plurality of stationary contacts.

In order to determine the direction from which a radio signal is received, a directional antenna array or a loop antenna may be rotated through 360° in azimuth with the direction being indicated by plotting the strength of the received signal as a function of the angle of rotation. However, in certain frequency ranges, such as from 10 to 60 megacycles, a directional antenna array may be too cumbersome for convenient rotation and yet the frequency may be too high for efficient operation of a loop antenna. In such a case, a number of directional antenna elements may be equally spaced about a vertical axis and sequentially connected to a receiver through a switch including one or more movable contacts sequentially engaged with stationary contacts respectively connected to the antenna elements.

In such an arrangement, one desirable feature is that the elapsed time in switching from one contact to the next should be as small as possible and it is also desirable that the coupling between the stationary contacts be as small as possible to minimize cross-talk. It is further desirable, of course, that the switch be simple, compact, efficient and reliable in operation and constructed of parts which are readily and economically manufactured and assembled. It is therefore the object of this invention to provide a switch having these desirable features.

According to this invention, a movable contact is driven in such a manner that its speed of movement is relatively low while it is in engagement with each stationary contact and relatively high when moving between the stationary contacts. With this arrangement, the elapsed time in switching between contacts is minimized and at the same time the stationary contacts may be spaced apart a substantial distance to minimize coupling therebetween.

Any variable speed drive arrangement could be used but preferably, a support element is arranged to be driven in such a manner that a point thereof moves in a path generally parallel to an imaginary line interconnecting adjacent stationary contacts, and means are provided resiliently urging the movable contact away from such point toward a position beyond such imaginary line. With this simple arrangement, the support element may be driven at a constant speed and the resilient means stores up energy while the movable contact engages a stationary contact with the stored energy being released to snap the movable contact into engagement with the next stationary contact. In addition, the pressure exerted between the contacts and the wiping action obtained between contacts minimizes contact resistance and insures reliable switch operation.

The support element is preferably rotatable with the stationary contacts arranged in arcuately spaced arrangement about the axis of rotation of the support element, and the movable contact is preferably carried by an arm

2

of resilient material so as to provide a very simple and yet efficient and reliable construction.

This invention thus provides a switch which is very simple in construction and yet highly efficient and reliable in operation. The switch has general application but is particularly advantageous in an antenna lobing system because of the fact that the elapsed time in switching between contacts is minimized while the contacts may be spaced apart a substantial distance to minimize coupling therebetween.

This invention contemplates other objects, features and advantages which will become more fully apparent from the following detailed description taken in conjunction with the accompanying drawings which illustrate a preferred embodiment and in which:

Figure 1 is a side elevational view of an antenna assembly incorporating a lobing switch constructed according to the principles of this invention;

Figure 2 is an elevational sectional view through the switch of the assembly of Figure 1;

Figures 3, 4 and 5 are sectional views respectively taken substantially along lines III—III, IV—IV and V—V of Figure 2; and

Figures 6 and 7 are sectional views respectively taken substantially along lines VI—VI and VII—VII of Figure 5.

Reference numeral 10 generally designates an antenna assembly in which a lobing switch unit 11 constructed according to this invention is used to sequentially connect the input of a receiver to a plurality of antenna elements 12. The switch unit 11 is supported at the upper end of a mast 13.

Each of the antenna elements 12 is secured to a hooked end portion 15 of a conductor 16 embedded in a support ring 17 of insulating material such as plastic with the conductors 16 extending radially in angularly spaced relation like the spokes of a wheel. The inner end of each conductor 16 is soldered to a lug 18. Screws 19 extend through the lugs 18 and through tubes or sleeves 21, with the ends of the screws 19 being threaded into a support ring 22 of insulating material which is supported on a flange ring 23 secured in assembly with the ring 17.

The tubes or sleeves 21 form stationary contacts and are disposed in spaced relation in a circle about the axis of the shaft 25 of an electric drive motor 24 supported on the flange ring 23.

The motor shaft 25 is coupled by a pin 26 to one end of a coupling shaft 27 the other end of which is coupled to the shaft 28 of a synchro torque transmitter 29 which generates a signal for the remote indication of the angular position of the shaft 28 and elements coupled thereto. The transmitter 29 is secured within a base 30 of inverted cup-shaped configuration which is slipped on the end of the mast 13. The ring 17 is supported from the base 30 through a bearing plate member 31 of inverted cup-shaped configuration which is also used to support a ball bearing assembly 32 for the coupling shaft 27.

A collar 33 is secured on the coupling shaft 27 and carries a ring 34 of insulating material. As shown in Figures 3 and 4, the ring 34 has a pair of blocks 35 and 36 secured to the upper face thereof with outwardly projecting arms 37 and 38 being secured at their inner ends to the blocks 35 and 36 and with contacts 39 and 40 secured to the outer end portions of the arms 37 and 38.

The arms 37 and 38 are of a resilient conductive material, preferably beryllium copper, and are of such length that in the unstressed condition thereof, the contacts 39 and 40 project outwardly beyond an imaginary circle at the inner edges of the stationary contacts defined by the tubes 21. With counter-clockwise rotation of the ring 34 and blocks 35 and 36 secured thereto (as viewed in

Figures 3 and 4), the contacts 39 and 40 will engage a pair of the contact tubes 21. With further counter-clockwise rotation, the arms 37 will be resiliently bent back in a clockwise direction and the contacts 39 and 40 will slide radially inwardly on the contact tubes 21. When the arms 37 and 38 are bent to such an extent that the contacts 39 and 40 are inside the contact tubes 21, the arms will be released and the resiliency thereof will snap them forwardly toward the next pair of contact tubes. Preferably, the position and length of the arms 37 and 38 is such relative to the position and spacing of the tubes 21 that when the contacts 39 and 40 move inside and past one pair of contact tubes, they will be snapped into engagement with the next pair of tubes. There is thus a minimum time delay in switching from one contact to the next and yet the stationary contacts are spaced a substantial distance from each other to minimize coupling therebetween.

The arms 37 and 38 are electrically connected to outer and inner coaxial slip rings 41 and 42 of conductive material mounted on the underside of the insulating ring 34 and engaged by brushes 43 and 44 mounted in sleeves 45 and 46 and urged into pressure engagement with the slip rings 41 and 42 by coiled compression springs 47 and 48 within the sleeves 45 and 46 which are pressed into insulator 49 affixed to the bearing plate 31. The sleeve 45 is formed to provide a first terminal post 50 projecting through the bearing plate 31 and the sleeve 46 is connected through a wire 51 to a second terminal post 52 also extending through the bearing plate 31. The terminal posts 50 and 52 are connected through wires 53 and 54 to terminal posts 55 and 56 insulatingly supported in the wall of the bearing plate 31, the posts 55 and 56 being arranged for connection through a suitable transmission line to the input terminals of a receiver.

The conductors of a cable 57 connected to the motor 24 and a cable 58 connected to the transmitter 29 are connected to a jack 59 supported in the wall of the bearing plate member 31, and a plug inserted in the jack 59 may be connected to a remote unit not shown including a position indicator actuated by the signal from the transmitter 29 and also including a power supply for the motor 24. A capacitor 60 in circuit with the motor 24 may be disposed within the bearing plate member 31.

It will be noted that in the illustrated antenna assembly, there are eighteen elements at equal spacings of 20° and the terminals 55 and 56 which may be connected to the receiver input are at any given instant connected to a pair of the antenna elements spaced 40° apart so that

the antenna is thus a sloping inverted V with an included angle of 40°. Such an antenna may have highly directional characteristics, and by plotting the receiver response with respect to rotation of the switch assembly, the direction from which a received signal emanates can be accurately determined. It will be apparent that the antenna elements may be of any desired length and the unit 11 may be of much smaller size relative to the length of the antenna elements than is the case with the assembly illustrated in Figure 1.

This invention thus provides a switch which is very simple in construction and yet highly efficient and reliable in operation. The switch has general application but is particularly advantageous in an antenna lobing system because of the fact that the elapsed time in switching between contacts is at a minimum while the contacts may be spaced apart a substantial distance to minimize coupling.

It will be understood that modifications and variations may be effected without departing from the spirit and scope of the novel concepts of the present invention.

I claim as my invention:

In an antenna lobing system; a support ring of insulating material; a plurality of angularly spaced radially extending conductors in said support ring; a plurality of antenna elements connected to the outer ends of said conductors to project therefrom in radial planes; a plurality of stationary contacts connected to the inner ends of said conductors and arranged in a circle in equi-angularly spaced relation about the axis of said ring; a contact support element rotatable about said axis, an electric drive motor for effecting continuous rotation of said support element, a pair of resilient leaf spring elements on said support element electrically insulated from one another and in constant angularly spaced relation and having length and spacings which are such relative to the positions and spacings of said stationary contact as to simultaneously move inside and past one pair of said stationary contacts to be simultaneously snapped into engagement with the next pair of said stationary contacts; and slip ring means on said support element connecting said pair of spring contact elements to a utilization circuit.
